UNITED STATES PATENT OFFICE.

CHARLES B. YOUNG AND CHARLES J. CASPARE, OF PITTSBURGH, PENNSYLVANIA,
ASSIGNORS TO PITTSBURGH PLATE GLASS COMPANY, A CORPORATION OF PENN-
SYLVANIA.

STORE-FRONT CONSTRUCTION.

Application filed July 21, 1920. Serial No. 397,940.

The invention relates to store front constructions. It has for its primary objects the provision of an improved construction which permits the setting of the glass with a minimum labor cost; which is of simple construction and relatively low cost; in which a maximum clearance is afforded between the edge of the glass and the metal fixtures surrounding it, so that breakage due to settling and consequent engagement of the edge of the glass with any rigid metal members tending to break the sheet is reduced; and in which the glass can be set entirely from the front while at the same time avoiding a showing from the front of screws or other holding devices for the metal cap plate tending to mar the appearance of the construction. Certain embodiments of the invention are illustrated in the accompanying drawings, wherein:

Figure 1 is a front view of the assembled construction with portions of the glass and front strip broken away to more clearly disclose the construction; Fig. 2 is an elevation looking at the rear of the front strip; Fig. 3 is a section on the line III—III of Fig. 1; Fig. 4 is a perspective view showing the construction at one of the clamps or securing means with the glass and front strip removed; Fig. 5 is a view similar to that of Fig. 1 of a modified construction; Fig. 6 is a rear elevation of the front strip; Fig. 7 is a section on the line VII—VII of Fig. 5; Fig. 8 is a section through a modified construction, and Fig. 9 is a front elevation of one of the securing wedges used in the construction of Fig. 8.

The construction is ordinarily referred to as a sash bar and is capable of a number of different embodiments all involving the same general principle but differing in matter of detail. In its essentials the construction comprises, a back strip adapted to engage the rear side of the glass, a base strip lying opposite or below the edge of the glass, spaced securing means mounted upon the base strip; and a front or cover strip having engaging means for interlocking with the securing means when the front strip is placed in position and moved lengthwise a short distance. The lower edge of the front strip also interlocks with the outer edge of the base strip, thus holding the lower edge of such front strip against outward move-

ment. This construction permits the glass to be secured entirely from the front and the arrangement whereby the front strip is locked in position by moving it longitudinally avoids the necessity of using screws or other similar devices for this purpose, thus simplifying the device and giving the construction a better appearance from the front. In one form of the device provision is made for moving the front strip against the glass as such front strip is moved longitudinally to lock it in position, this preferably being accomplished by means of wedges, but in other forms of the device the application of the cover strip does not perform this function, the glass being secured in position by means of clamps independent of the front or cover strip, and the front strip being subsequently applied in the manner heretofore referred to.

The latter form of construction being the simpler will be described first, reference being had to Figs. 1 to 4, which illustrate this construction. As here shown, 1 is the wood framework in which the sash bar is set, 2 is the glass, 3 is the back strip, 4 is the base strip, which in this instance is integral with the back strip; 5 are spaced brackets secured in position by means of the screws 6, 7 are the clamps mounted slidably upon the brackets for movement toward and from the glass, and 8 is the front or cover strip.

The back strip 3 may be turned outwardly as indicated at 9 to provide a gutter, and spaced at intervals along this strip are lead bearing strips 10, the spacing of which provides for the passage of the drainage. The clamps 7 are also preferably provided on their faces with lead bearing strips 11.

The brackets 5 may, if desired, be pressed out of the material of the base strip 4 and are of dovetail shape, as indicated in Fig. 4. The clamps 7 are slotted so as to fit the dovetail brackets 5 and are provided with lugs 12 carrying the screws 13 which provide for clamping the members 7 in any desired position of adjustment, depending upon the thickness of the glass.

The front strip 8 has its upper edge bent or hooked over forming the securing lugs 14 (Fig. 2), which are adapted to be engaged by the clamps 7. The outer edge of the base strip 4 is bent up as indicated at 15 to provide a holding recess, and the lower edge

of the outer strip is bent back as indicated at 16 to engage in such recess.

In assembling the device the sheet of glass is positioned with its edges resting upon a pair of wood or fibre blocks, not shown. The clamps 7 are then mounted on the brackets 5 and pushed up tightly against the glass, after which the screws 13 are screwed down to lock the clamps in position. The front or cover strip 8 is now applied by hooking its lower edge beneath the edge of the base strip as indicated in Fig. 3, with its upper edge bearing against the glass and with the lugs 14 to one side of the clamps 7. The strip 8 is then slid longitudinally until the lugs or holding devices 14 come behind the clamps. This, of course, leaves a space at one or both ends of the front strip 8, but such spaces are relatively short and are covered by the corner caps ordinarily used in this general type of construction, such corner caps being fastened in position by the usual screws. It will be seen that the construction is easily assembled entirely from the front of the window and that this operation is relatively simple and easily accomplished. The clamps 7 are easily and rapidly positioned and secured in place and the front strip 8 secured in position at a single operation, the interlocking arrangement at the upper and lower edges of this strip giving a very secure attachment and one which is of neat appearance. The front strip is preferably slotted at its lower edge, as indicated at 17, in order to provide for drainage. It will be noted that a relatively wide space is left at 18 between the edge of the glass and the brackets 5, so that considerable settling can occur without danger of the glass coming in contact with a rigid metal fixture, which would tend to cause breakage.

The type of clamp illustrated is only one of a number which may be employed, such clamp being preferably used because there is no means for pushing them up too tightly against the glass and causing breakage, such as often occurs in other types of construction where the clamps are operated by screws or similar power devices. It will be understood, however, that the invention is not limited in this particular, power means for moving the clamps not being employed for the reason above indicated, but may be readily employed in a variety of forms if so desired and to meet special conditions or requirements.

Figs. 5, 6 and 7 illustrate a modified type of construction in which the clamping action is secured by the longitudinal movement of the front strip, such longitudinal movement serving to lock the base strip in position and at the same time press it against the glass, the front strip in this case serving as the clamping means. In this construction 18^a is

the wood framework, 19 is the back strip, 20 is the glass, 21 is the base strip, and 22 is the front strip.

In this arrangement what is known as a "kalomine" construction is employed behind the glass, such construction involving the strip 19, another metal strip 23 and a wood filler 23^a, the lead bearing strips being omitted in this construction and drainage being permitted either by lack of complete contact between the strip 19 and the glass or by grooving the strip at intervals, these being well known expedients in the art and constituting no part of the present invention. The base strip 21 is provided at intervals with punched up dovetail lugs 24 to which are securely attached bracket members 25, each provided with two wedge portions 26, as indicated in Fig. 5. The upper edge of the front strip 22 is bent around as shown at 27, to form a holding recess, and spaced at intervals in this recess are locking loops 28 (Fig. 6), such loops being clamped in the recess 27 so that they will move with the front strip. The lower edge of the front strip 22 is preferably hooked round the outer edge of the base strip 21, as indicated at 29.

In assembling this construction, the glass 20 is placed upon wood blocks as in the other form of construction and the front strip is hooked over the outer edge of the base strip with the locking loops 28 in alignment with the brackets 25. The front strip is now moved longitudinally so that the loops pass over the ends of the wedge portions 26. As this movement continues the wedge action pulls the loops 28 downward, thus moving the upper edge of the front strip into contact with the glass, the tightness of such contact depending upon the extent to which the front strip is moved. The friction involved in such movement, however, is such that it renders it impossible to apply such a pressure upon the glass as would tend to break it. It will be seen that this sash bar may be applied even more quickly than the one of the construction of Figs. 1 to 4. Also that it involves the same principle of locking the front strip by moving it longitudinally so that spaced locking means are brought into engagement.

Figs. 8 and 9 illustrate a somewhat different construction involving the same general idea as Fig. 7. In this construction the back strip 31 is made as illustrated with the base strip 32 integral therewith and having a hooked portion 33 at its outer edge. The front strip 34 and loops 35 are the same as in the construction of Fig. 7, but the locking wedge member 36 is somewhat different, such wedge member fitting at its outer edge in the hooked portion 33 of the base strip and at its inner edge being held in position by means of the machine screws 37. This member 36 is provided with two wedge parts

38, and the method of fitting the glass and applying the front strip is the same as described in connection with the construction of Figs. 5, 6 and 7.

5. What we claim is:—

1. In combination in a store front construction having a glass plate therein, a back strip opposite the rear face of the glass, a base strip opposite the edge of the glass, a

10 front strip having interlocking engagement at its lower edge with the base strip, spaced plate engaging devices beneath the front strip, and spaced means on the front strip adapted to interlock with said engaging devices and be released therefrom when such strip is shifted longitudinally.

15 2. In combination in a store front construction having a glass plate therein, a back strip opposite the rear face of the glass, a base strip opposite the edge of the glass, a front strip having its lower edge hooked around the outer edge of the base strip, spaced plate engaging devices fixed beneath the front strip, and spaced means on the front strip adapted to interlock with said engaging devices and be released therefrom when such strip is shifted longitudinally.

20 3. In combination in a store front construction having a glass plate therein, a back strip for engaging the rear face of the glass, spaced supporting brackets fixed against movement with respect to the back strip, a front strip along the front of the glass in opposition to the back strip and having its edge recurved to provide holding recesses, and clamps for engaging the glass plate mounted movably on said brackets operable from the front of the glass and engaging in said holding recesses in the front strip.

25 4. In combination in a store front construction having a glass plate therein, a back strip for engaging the rear face of the glass, a base strip opposite the edge of the glass and extending to the front thereof, spaced supporting brackets fixed with respect to the back and base strips, a front strip along the front of the glass interlocking at its lower edge with the outer edge of the base strip and having spaced recurved portions at its upper edge, clamps for engaging the glass plate mounted movably on said brackets and engaging said recurved portions of the front strip, and securing means for the clamps operable from the front of the glass before said front strip is applied.

30 5. In combination in a store front construction, a back strip for engaging the rear face of the glass, a base strip opposite the edge of the glass and extending to the front thereof, spaced supporting brackets fixed with respect to the back and base strips, a front strip along the front of the glass interlocking at its lower edge with the outer

edge of the base strip and having spaced recurved portions at its upper edge, clamps for engaging the glass plate mounted slidably on said brackets and engaging said recurved portions of the front strip, and means operable from the front of the glass for securing said clamps in adjusted position before said front strip is applied.

35 6. In combination in a store front construction, a back strip for engaging the rear face of the glass, a base strip opposite the edge of the glass and extending to the front thereof, spaced supporting brackets fixed with respect to the back and base strips, a front strip along the front of the glass interlocking slidably at its lower edge with the outer edge of the base strip and having spaced engaging lugs at its upper edge, and clamps adjustably mounted on said brackets and adapted to engage the glass and said clamps being adapted to engage said lugs when the front strip is moved longitudinally to operative position.

40 7. In combination in a store front construction securing the edge of a glass plate in a supporting framework, a back strip opposite the rear face of said plate, a base strip opposite the edge of the plate having its forward edge formed to provide a locking recess, clamping means securing the plate against the back strip and accessible from the front of the glass, and a front or cover strip having releasable interlocking engagement in said recess at the forward edge of the base strip and with the clamping means.

45 8. In combination in a store front construction securing the edge of a glass plate in a supporting framework, a back strip opposite the rear face of said plate, a base strip opposite the edge of the plate, clamping means securing the plate against the back strip and accessible from the front of the glass, and a front or cover strip having its lower edge hooked beneath the forward edge of the base strip and its upper edge engaged releasably with the clamping means so that the front or cover strip may be released without disengaging the clamping means from the glass plate.

50 9. In combination in a store front construction securing the edge of a glass plate in a supporting framework, a back strip opposite the rear face of said plate, a base strip opposite the edge of the plate having its forward edge formed to provide a locking recess, clamping means securing the plate against the back strip and accessible from the front of the glass, and a front or cover strip having releasable interlocking engagement in said recess with the forward edge of the base strip and with the clamping means, and adapted to be locked in position and released therefrom by a relative movement with respect to the clamping

means, but without adjusting or releasing the engagement of the clamping means with the glass plate.

10. In combination in a store front construction having a glass plate therein and a shoulder opposite the rear face of the glass, a base strip opposite the edge of the glass, a front strip having interlocking engagement at its lower edge with the base strip, spaced plate engaging devices beneath the front strip, and spaced means on the front strip adapted to interlock with said engaging devices and be released therefrom when such strip is shifted longitudinally.
15. 11. In combination in a store front construction securing the edge of a glass plate in a supporting framework having a shoulder in opposition to the rear face of the plate, a base strip opposite the edge of the plate having its forward edge formed to provide a locking recess, plate clamping means in opposition to the front face of the plate and a front or cover strip having releasable interlocking engagement in said recess at the forward edge of the base strip and with the clamping means, the said clamping means being operable from the front of the plate when the cover strip is removed.
20. 12. In combination in a store front construction securing the edge of a glass plate, a window framing in opposition to the rear face of the plate and to its edge, plate clamping means releasably secured in opposition to the front face of the plate adjacent its edge, and a front or cover strip lying over the clamping means and releasably engaging the clamping means, the said clamping means being operable from the front of the plate when the cover strip is removed.
25. 13. In combination in a store front construction securing the edge of a glass plate, a window framing in opposition to the rear face of the plate and to the edge thereof, securing means fastened against the framing adjacent the edge of the plate, plate clamping means in opposition to the front face of the plate and operable from the front of such plate, and a front or cover strip lying over the clamping means and having releasable interlocking engagement at one edge with the clamping means and at its other edge with the securing means.
30. 14. In combination in a store front construction for securing the edge of a glass

plate, a window framing in opposition to the rear face of the plate and to its edge, spaced clamps mounted for movement toward and from the front face of the glass, screws extending at right angles to the line of movement of the clamps for holding them in adjusted position and a cover strip lying over the clamps and held releasably in such position.

15. In combination in a store front construction for securing the edge of a glass plate, a window framing in opposition to the rear face of the plate and to its edge, spaced clamps mounted for movement toward and from the front face of the glass, screws extending at right angles to the line of movement of the clamps for holding them in adjusted position and a cover strip lying over the clamps and held releasably in such position by means of interlocking engagement with said clamps.

16. In a store front construction, a window casing, an element secured to the casing and in contact with the window glass for firmly clamping such glass in place, a moulding strip covering said element and having a flange retained by said element in proximity to the glass, and an anchoring device secured to said window casing; the outer edge of said moulding strip being detachably interlocked with said anchoring device.

17. In a store front construction, a window casing, a window glass in said casing, an element secured to the casing and exerting pressure to hold said window glass clamped in place, an anchoring device secured to said casing, and a moulding strip adapted to be secured in or removed from engagement at its opposite edges with said clamping element and anchoring device after said glass has been clamped in position.

18. In a store front construction, a window casing, a window glass in said casing, an element secured to the casing and having direct contact with the glass and firmly clamping the same in place, an anchoring device secured to said casing, and a moulding strip adapted to be detachably engaged at one of its edges with said clamping element after the glass has been clamped in position, and at its other edge to have detachable engagement with said anchoring device.

CHARLES B. YOUNG.
